ATTORNEY

UNITED STATES PATENT OFFICE.

HARLAN S. WEBSTER, OF CANTON, OHIO.

ROTARY-BLOWER SPARK-GAP.

1,256,405.

Specification of Letters Patent. Patented Feb. 12, 1918.

Application filed March 3, 1917. Serial No. 152,381.

To all whom it may concern:

Be it known that I, HARLAN S. WEBSTER, a citizen of the United States, residing at Canton, in the county of Stark and State of Ohio, have invented new and useful Improvements in Rotary-Blower Spark-Gaps, of which the following is a specification.

This invention relates to spark gap apparatus and more especially to such apparatus having means for cooling the electrodes.

The primary object of the invention is to provide an improved spark gap apparatus having a rotary portion adapted to produce centrifugal discharge of air to cool the electrodes of the apparatus.

Another object is to provide in such an apparatus means whereby the sparks produced will be of uniform length.

A further object is to provide electrodes adapted to utilize more efficiently the air current produced in such an apparatus.

Other objects will appear upon examination of the accompanying drawings and the description and claims below.

In the drawings,

Figure 1 is a side elevation of the apparatus.

Fig. 2 is an end view of the same.

Fig. 3 shows details of the apparatus.

Referring now to the drawings in detail, 1 represents a base or a supporting structure having vertically extending members 2 suitably provided toward the upper extremity with journals 3 having mounted therein for rotation a shaft 4. Shaft 4 is provided toward one extremity with means for producing rotation, here shown as a pulley 5 and is further provided with means for supporting the rotary electrodes, such means being illus-

trated as a spider 6. Securely attached to the outer portions of spider 6 is an electrode element preferably comprising two annular members of conducting material, 7 and 8 respectively, spaced apart concentrically to

shaft 4 and in parallelism each to each. Secured between the inner faces of members 7 and 8 are a plurality of electrodes 9, and these electrodes are preferably spaced apart in an annular row concentric to shaft 4.

Conveniently located toward each extremity of base 1 are standards 10 having toward the upper extremities stationary electrode elements 11 alined with and in proximity to revoluble electrodes 9. Electrode members

12 are spaced apart and are preferably disposed concentrically to shaft 4. These mem-

bers are here shown as having a width greater than the spacing between electrodes 9, but I may provide electrodes 9 of a width sufficient to overlap the spaces between the electrodes 12, the purpose in either case being to prevent variation in the length of the spark gap during rotation of the revoluble element.

Suitable means of insulation are provided between the various electrodes and the other portions of the apparatus.

From the above description and drawings, the operation of the apparatus will become apparent.

Upon the stationary electrodes being connected with a suitable source of high tension electricity such as used for X-ray apparatus or wireless telegraphy, a discharge will result between one of the stationary elements 75 and the revoluble electrode element and from said revoluble element to the other stationary electrode element. Upon the revoluble element being now rotated by connection of any suitable source of power to pulley 5, a centrifugal blast of air will result, penetrating the passages between the various electrodes and thoroughly cooling the same. This blast will eliminate any tendency toward formation of an arc, thereby causing production of highly damped oscillations of great efficiency. The stationary electrodes being of a width greater than the gap between the revoluble electrodes and being mounted concentric thereto, the discharge occurring will be of uniform length, which is a very desirable feature for certain purposes and especially wireless telegraphy.

While I have here shown and described a preferred form of my invention for purposes of illustration, such embodiment is not to be interpreted as limiting the spirit and scope of the invention.

What I claim is:

1. In electric discharge apparatus, a revoluble element comprising spaced annular members, an annular row of spaced radially disposed electrodes between said members, said electrodes adapted to produce a radial discharge of fluid; a relatively stationary element comprising a plurality of spaced electrodes, said electrodes disposed concentrically to said revoluble element, and adapted to receive an electric discharge from said revoluble element and further adapted to be cooled by fluid discharged from the revoluble element through such spaces.

2. In electric discharge apparatus, a revoluble element comprising spaced annular members, an annular row of spaced radially disposed electrodes between said members, 5 said electrodes adapted to produce a radial discharge of fluid, a relatively stationary element comprising a plurality of spaced electrodes disposed concentrically to said revoluble element, and adapted to receive an electric 10 discharge from said revoluble element, and further adapted to be cooled by fluid discharged from the revoluble element through such spaces; a second stationary element similarly formed to the first mentioned stationary 15 element, and likewise adapted to be cooled by fluid discharged from the revoluble element and further adapted to transmit an electric discharge to the revoluble element.

3. In electric discharge means, a revoluble element and a plurality of electrodes on said element, said element formed with passages between said electrodes adapted to discharge of fluid; a relatively stationary element comprising a plurality of electrodes, said stationary element formed with passages between said electrodes adapted to receive and conduct fluid discharged from said revoluble element to cool said electrodes of the stationary element; the electrodes of one of said elements having a dimension in the direction of rotation greater than the corresponding dimension of the passages between the electrodes of the other element.

In testimony whereof I affix my signature.

HARLAN S. WEBSTER.
